UNITED STATES PATENT OFFICE

2,508,678

ROTARY PUMP

Robert MacDougall, Rock Falls, Ill.

Application April 17, 1946, Serial No. 662,873

6 Claims. (Cl. 103—103)

1

My invention has reference to a rotary pump, of the turbine type, and embraces a device of that character which is capable of a multi-stage operation. As set forth herein it embodies a two-stage machine, with a multiplied amount of force generated by a single impeller. It belongs more specially to a smaller class of pumps, for use on farms and properties not equipped with the usual water power facilities. It is of a simple and compact construction, and is possessed of a maximum amount of efficiency and capacity.

Most of the smaller pumps now in use have restricted water passages, resulting in high frictional losses and low capacity, which are overcome in the present invention. Any two-stage pump that is commonly known is fitted with an impeller for each pump, increasing the cost of production, and adding to the frictional and other difficulties. This arrangement has no great advantage over the use of two separate pumps.

By the use of a single impeller in my pump, and a double stage of liquid flow, passages are provided of approximately twice the area for the same capacity in a single pump, and providing double the pressure. The impeller is divided into five sections, succeeding each other in rapid sequence, two successive sections of which are acting continuously on one side of the rotor, and two on the opposite side, to discharge alternately into the first stage passages and into the second stage passage. The two stages are produced simultaneously and continuously by the five impeller vanes. One vane is partially sealed off during the operation by the cut-off separation between the first and second stages. It has been demonstrated that under a fairly high head this pump can be made to discharge round five thousand gallons of water per hour. The water passage in the first stage is double the width of the impeller, thus the water in this passage is boosted along by the rotation of the impeller circumference as well as by the water discharge.

At the intake of the pump is a distributing device which acts as a separator, in the first instance directing the flow of liquid toward the first stage, and in the second instance diverts the flow toward the second stage.

The water passages of the impeller occupy only about seventy per cent of the outer circumference, allowing the discharge water in the casing to be boosted along to hold up velocity and counteract the tendency to eddy back into the following side of the impeller vanes.

In a pump of the size shown herein, having an 55

impeller with a diameter of approximately four inches, a relatively small electrical motor can be employed for the operation thereof, such a motor of one-half horsepower being sufficient. Such a pump has been demonstrated as being capable of discharging sixteen and sixty-six hundredths gallons per minute on a total of fifty-six (56) feet head pressure.

The above named, and other features and advantages of the invention will more fully appear from the following specification, reference being had to the accompanying drawings, in which—

Fig. 1 shows the invention in side elevation, partly in medial longitudinal section.

Fig. 2 is a cross-section on the broken line 2—2 of Fig. 1, enlarged.

Fig. 3 is a front face view of the impeller rotor and appurtenant parts.

Fig. 4 is a sectional detail of the impeller on the line 4—4 of Fig. 5, partly broken away.

Fig. 5 is a longitudinal section of the impeller and casing parts, similar to the showing in Fig. 1, enlarged.

Fig. 6 is a side view of the distributor 19, with appurtenant parts in section, of about full size.

Fig. 7 is a lower plan view thereof, detached.

Fig. 8 is an upper plan view thereof.

Fig. 9 is a cross-section on the dotted line 9—9 of Fig. 7.

30 In the first two figures of the drawing the reference number 11 indicates the main casing of cylindrical form, and provided with a side plate 12, at a central point in which is a cylindrical extension 13, having a bore 14, opening into the casing. At one side of said cylinder is an extension 15, provided with an intake opening 16, connecting with the bore 14 at the lower side thereof. The outer end of the cylinder 13 is closed by a plate 17, held by screws 18, entering

40 screw holes in the outer end of the cylinder. The plate 17 also provides a support for one end of a distributor member 19, extending inwardly from the inner face of the plate, and preferably integral therewith. The particular form and purpose of said distributor device will be herein-after more fully set forth.

The casing 11 is also provided with a closure plate 20, secured thereto by means of a flange 21 and screws 23 therein entering the part 11. 50 Projecting inwardly at an angle with the flange 21 is a flange 22, forming the outer wall of the space within the casing. The casing is supported on a base 24, mounted on feet 25.

Revolutionally mounted in the casing is a rotor 26, extending radially from a cylindrical hub 27, ro-

tatable in bearings 28 in the casing. The hub is engaged by one end of a shaft 29, connected with the driveshaft 30 of an electric motor 31, by means of couplings 32. The motor 31 is also supported on the base 24.

The inner face of the rotor 26 is provided with a plurality of vanes 35 and 36, of a turbine type, the first of which extend from the hub 27 to the periphery of the rotor, and the latter of which only extend a short ways in from the circumference. Between the vanes near the center are spaces 37, developing outwardly into channels 38, extending to the circumference of the rotor. The inner ends of the vanes 35 are formed integrally with the hub 27, and at intervals coinciding with the positioning of said vanes the hub is provided with openings 39, communicating with the spaces 37. In the inner end of the hub is a cone 27a, diverting water coming in thru the bore 14.

On the lower side of the casing 11 is a water conduit 40 (Fig. 3), in an enlargement 40a of the casing, with the outer end of which is connected a tubular conductor 41, of circular form, to lend a minimum of resistance to the flow of the liquid therethrough. The opposite end of the conductor 41 is held in a collar 42 on the cylinder 13, and connected with an opening in the upper part of said cylinder. The combined passage 40 and conductor 41 comprise the first stage of the pump, and water entering the cylinder and passing outwardly therethrough by the friction force created by the rotor vanes, is carried through said first stage and back into the central cylinder, from which it is carried into the second stage, consisting of a conduit 43 on the upper part of the casing 11, in an enlargement 44, which conduit ends in an outlet at 45. Connection can be made with said conduit for the discharge of the liquid as desired. In the upper part of the casing is a block 46, positioned so as to prevent any rearward movement of the water or mingling thereof between the two passages. At the lower side of the casing is a block 47, forming an additional separation for the passages 40 and 43, and preventing a return movement of the water. The primary movement carries the water into the conduit 40 and the conductor 41 and back to the center of the pump, as before mentioned, and then outwardly again through the conduit 43, the second flow being separated from the primary flow in the manner hereinafter described.

The blocks 46 and 47 cut off approximately thirty-six degrees at each side of the casing, as between points indicated by broken lines C and D at the upper side of Fig. 3 and by the broken lines E and F at the lower side of said figure, and as before mentioned the rotor is provided on its face with five water passage sections, each subdivided and forming ten passages in all, with a multiple suction capacity and driving force. This number of sections can be varied, but is preferred.

Adjacent to the rotor 26 is a circular plate 48, integral with a hub 49, having a reduced end portion rotatably mounted in a bearing 50 in a cylindrical extension 52 of the casing plate 20. The rotor 26 and plate 48 are united by screws 51, so as to rotate as a unit. The plate 20 has a further extension 53, closed by a plate 54, and between said extension and the shaft 29 is a packing ring 55. The plate 48 encircles the inner end of the hub 27.

The diversion of the flow of liquid in the pri-

mary movement to and through the first stage apparatus, and in the secondary movement to that of the second stage is controlled by means of the distributor 19, before referred to which is shown more particularly in Figs. 6 to 9, inclusive, and which includes a cylindrical body portion 60 and reduced end portion 61, formed by a cut away channel 62 on the lower side of the member and a cut away channel 63 on the upper side thereof. In the end of the part 61 is a recess 64 conforming to the shape of the cone 27a in the inner end of the hub 27. One edge of the channel 61 is curved as at 66, and when the distributor is in its normal position water entering the intake 16, by the suction force of the impeller is diverted into the cylinder 21, and out through the openings 39 on the lower side of the distributor. The side edges of the end piece 61 are tapered toward the inner end, and the inner walls of the hub 27 are correspondingly tapered, so that the water is prevented from passing from one side of the distributor to the other. As a consequence the liquid which first enters the hub 27 is carried outwardly through openings 39 at the lower side thereof, and is drawn into the first stage. Upon its return through conductor 41 it passes to the upper side of the distributor, and out through the openings 39 at the upper side thereof, and is forced into the second stage.

The channel 63 in the upper face of the distributor is provided with a cross-channel at 67, in line with the end of conductor 41, into which the stream of water is discharged from said conductor, and through which it is directed into the channel 61 and upper part of the cylinder.

As before stated, the water passages of the impeller are so constructed and arranged as to cause the water handled thereby to be boosted along to prevent loss of velocity and to counteract any tendency of the liquid eddying back into the following side of the impeller vanes. It has also been demonstrated that by the use of a single impeller and double stage of liquid flow, as set forth herein, and by increasing the size of the water passages, double the amount of pressure can be generated than that of the usual single impeller pump.

Changes can be made in the manner of construction and operation of the various parts of the invention, without departing from the spirit thereof, as set forth and claimed herein.

What I claim, and desire to secure, is:

1. In a pump, a casing provided with primary and secondary water passages, and means for discharge from said secondary passage, an impeller rotatably mounted in said casing provided with a plurality of turbine channels communicating outwardly with said water passages, means for rotating said impeller, means for supplying said impeller with a volume of water at a central point, communicating with said channels at their ends, means for conducting a stream of water from said primary passage to said central point, forming with said primary passage a first stage of flow, and means for the control of flow of said water at said central point, to divert it in the first instance into said primary passage and in the second instance into the secondary passage, forming the second stage of movement thereof.

2. In a rotary pump having a casing capable of a first and second stage of movement therein, and an impeller mounted therein for rotation provided with a plurality of turbine channels operating outwardly in said casing, a central cylin-

drical intake having a plurality of openings communicating with said channels, a first stage of movement adapted to receive a volume of water from said impeller channels, and having connections to convey the water back to said intake, a secondary stage of movement and discharge therefor, and a distributing member operating in said intake, to divert the water from said intake successively into said first stage and into the secondary stage, with a multiple amount of force.

3. In a rotary pump, having a casing, and impeller rotatably mounted therein, provided with a plurality of turbine channels, operating outwardly, an intake comprising a cylindrical member provided with outlets into the impeller channels, and a distributor supported in said intake, compelling a discharge of liquid therefrom at the lower side of the distributor into the lower circumference of the impeller, and from the upper side of the distributor into the upper circumference of the impeller, and an outlet therefor.

4. In a rotary pump having a casing provided with conduits for a first and second stage of movement therein, and outlet therefor and an impeller mounted therein for rotation provided with a plurality of channels operating outwardly into said first and second stages, a central cylindrical intake having a plurality of openings into the impeller channels, and a distributor device in said intake, having a circular body portion and channels on opposite sides for diverting the water in the first operation to channels on the lower side of the impeller and in the second operation to channels on the upper side thereof.

5. In combination with a pump casing and support therefor, a primary water conduit in said casing, and tubular extension therefrom, a secondary water conduit and outlet therefrom, an impeller rotatably mounted in said casing for delivery of water to said conduits, provided with a plurality of turbine channels means for rotat-

ing said impeller, an intake cylinder at a central point of said impeller, provided with discharge passages thereto, into said channels and a distributor member supported in said intake cylinder provided with a cut-away channel on its lower side providing a water discharge to the passages in the lower side of the cylinder, and having a cut-away channel in its upper side registering with said tubular extension and conducting the flow therefrom to passages in the upper side of said intake cylinder.

6. In a rotary pump having a casing fitted with a two-stage water movement, one of which comprises a passage having a return to a central part 15 of the casing, and the other of which consists of a passage having a discharge outlet, and an impeller rotatably mounted in said casing provided with a plurality of turbine channels communicating outwardly with said passages, having a central cylinder with openings into the turbine channels at their inner ends, an intake cylinder centrally of the casing opening into the impeller cylinder, and a distributor in the last-named cylinder extending into the impeller cylinder forming a divider between the upper and lower parts thereof, to conduct a flow of liquid 20 from the intake cylinder to the openings in the lower part of the impeller cylinder, and from the return flow from the first stage to the openings 25 in the upper part of the impeller cylinder.

ROBERT MACDOUGALL.
